GOLF PRACTICE PUTTING CUP

Oscar Cohen, 125—10 Queens Blvd., Kew Gardens, N.Y.

Filed June 11, 1962, Ser. No. 70,495

Term of patent 3½ years

(Cl. D34—5)

FIG. 1 is a perspective view of a golf practice putting cup, showing my new design;

FIG. 2 is a sectional view taken on the line 2—2 of FIG. 1; and

FIG. 3 is a sectional view taken on the line 3—3 of FIG. 1.

The characteristic feature of my design resides in the one-piece molded practice putting cup of the configuration disclosed having a wedge-shaped planar surface leading to the hole and rimless arcuate edges falling away from the plane surface and hole, all as shown.

I claim:

The ornamental design for a golf practice putting cup, substantially as shown and described.
